UNITED STATES PATENT OFFICE

WINIFRED L. GIBBONS, OF PROVIDENCE, RHODE ISLAND, ASSIGNOR TO C. G. KING & CO., INC., OF PROVIDENCE, RHODE ISLAND

DESIGN FOR A SHOE LACE TASSEL

Application filed January 29, 1932. Serial No. 42,662. Term of patent 3½ years.

To all whom it may concern:

Be it known that I, WINIFRED L. GIBBONS, a citizen of the United States, residing at Providence, in the county of Providence and State of Rhode Island, have invented a new, original, and ornamental Design for Shoe Lace Tassels, of which the following is a specification, reference being had to the accompanying drawings, forming part thereof.

In said drawings, Fig. 1 is a front face view,

and Fig. 2 is a top plan view of the upper element of the design.

I claim:

The ornamental design for a shoe lace tassel as shown.

Signed at Providence, in the county of Providence and State of Rhode Island, this 28th day of January, A. D. 1932.

WINIFRED L. GIBBONS.
